UNITED STATES PATENT OFFICE.

HARRY L. PERRYMAN, OF LINCOLN, NEBRASKA.

CORKSCREW.

SPECIFICATION forming part of Letters Patent No. 257,062, dated April 25, 1882.

Application filed February 28, 1882. (No model.)

To all whom it may concern:

Be it known that I, HARRY LEONARD PERRYMAN, of Lincoln, in the county of Lancaster and State of Nebraska, have invented a new and Improved Corkscrew; and I do hereby declare that the following is a full, clear, and exact description of the same, reference being had to the accompanying drawings, forming part of this specification, in which—

10 Figure 1 is a side view of my improved corkscrew. Fig. 2 is a longitudinal section taken on the line *x x*, Fig. 1; and Fig. 3, a transverse section taken on the line *y y*, Fig. 1.

15 My invention relates to improvements in corkscrews; and it consists in the peculiar construction and arrangement of the parts, whereby in the rapid movement of the handle upward in drawing a cork it is suddenly stopped, thereby giving a jerk to the cork and drawing it more readily than by the ordinary method, in which a continuous pull is exerted upon the cork.

20 In the accompanying drawings, *a* represents the handle of my improved corkscrew, of the usual construction.

25 *b* represents a tube secured at one end to the middle of the handle, and provided with the longitudinal slots *c c*, lying opposite each other.

30 *d* represents the shank of the corkscrew, provided at its lower end with the screw *l*, of the usual construction, and near its upper end with the opposite studs, *h h*, adapted to fit in

the slots *c* and guide the shank *d* in its reciprocations in the tube *b*, and act as stops to the 35 tube *b* in its upward and downward movements.

In practice, in drawing a cork from a bottle the screw *l* is inserted into the cork in the usual manner, the handle being pressed down so that the shank of the corkscrew is inserted 40 in the tube, a rapid upward pull is then given to the handle, and the tube secured thereto slides rapidly up the shank until the lower ends of the slots *c c* strike the opposite studs or stops, *h h*, near the upper end of the shank *d*, when 45 a sudden jerk is imparted to the latter and its screw and to the cork, thereby more readily drawing the cork than in the ordinary method of drawing it, in which the cork is subjected to a continuous pull. 50

What I claim as my invention is—

1. The combination, with a corkscrew provided with a shank, *d*, of mechanism, substantially as described, whereby in drawing a cork a sudden jerk is imparted thereto, substantially 55 as specified.

2. The combination, with the tube *b*, provided with the opposite slots, *c c*, and handle *a*, secured to one end of the tube, of the screw *l* and shank *d*, having stops *h h*, substantially 60 as described, and for the purpose set forth.

HARRY LEONARD PERRYMAN.
